UNITED STATES PATENT OFFICE

164,210

KNIFE OR SIMILAR ARTICLE

John O. Van Koert, Newburyport, Mass., assignor to Towle Manufacturing Company, Newbury-port, Mass., a corporation of Massachusetts

Application December 28, 1950, Serial No. 13,606

Term of patent 14 years

(Cl. D54—12)

To all whom it may concern:

Be it known that I, John O. Van Koert, a citizen of the United States of America, residing at Newburyport, in the county of Essex and Commonwealth of Massachusetts, have invented a new, original, and ornamental Design for a Knife or Similar Article, of which the following is a specification, reference being had to the accompanying drawings, forming a part thereof, and wherein

Fig. 1 is a side elevational view of a knife, showing my new design, the opposite side presenting substantially the same appearance;

Fig. 2 is a top plan view;

Fig. 3 is a bottom plan view; and

Figs. 4, 5 and 6 are sectional views of the knife on lines 4—4, 5—5 and 6—6, respectively, of Fig. 1.

I claim:

The ornamental design for a knife or similar article, substantially as shown and described.

JOHN O. VAN KOERT.
